UNITED STATES PATENT OFFICE.

IKE BRATCHER AND OSCAR BURGHARDT, OF PROTECTION, KANSAS; SAID BURGHARDT
ASSIGNOR TO SAID BRATCHER.

CALF FEEDER.

1,426,252.

Specification of Letters Patent. Patented Aug. 15, 1922.

Application filed April 25, 1921. Serial No. 464,119.

To all whom it may concern:

Be it known that we, IKE BRATCHER and OSCAR BURGHARDT, citizens of the United States, residing at Protection, in the county 5 of Comanche and State of Kansas, have invented new and useful Improvements in Calf Feeders, of which the following is a specification.

This invention relates to improvements in 10 calf feeders, and comprehends the provision of a device which is adapted for use in conjunction with an ordinary pail or bucket, the invention embodying amongst other features a hollow tube adapted to be arranged 15 centrally of the bucket and through which tube the milk is sucked, the tube being encased in a sleeve of rubber or other suitably soft material so as to protect the mouth of the calf from injury.

20 The nature and advantages of the invention will be better understood when the following detailed description is read in connection with the accompanying drawing, the invention residing in the combination, construction, and arrangement of parts as 25 claimed.

30 In the drawing forming part of this application, like numerals of reference indicate similar parts in the several views and wherein:

Figure 1 is a vertical sectional view through a pail or bucket showing the invention associated therewith.

Figure 2 is a top plan view.

35 Figure 3 is a view of the device removed from the receptacle, partly in section.

Referring to the drawing in detail, 10 indicates a pail or any suitable receptacle adapted to contain the liquid, and with 40 which the feeder is designed for use.

The feeder embodies a plurality of elements 11 which may be constructed from any suitable material, preferably wire, the elements having their corresponding extremities secured in any suitable manner to the bottom of the bucket and equi-distantly spaced at points from the center thereof. These elements preferably terminate to provide loop 12 which repose upon the bottom 50 of the receptacle to receive fastening elements 13 which are passed through openings in the bottom, washers 14 being used to provide a fluid tight connection as will be readily understood. The elements 11 extend to

ward each other being grouped centrally of 55 the receptacle and are embedded in a sleeve-like member 15 of rubber or other suitable material, the sleeve encasing a metallic tube 16, the latter being supported by the sleeve as shown. The sleeve is adapted to project 60 an appreciable distance above the upper end of the receptacle, so as to be conveniently accessible, it being understood that the calf draws the liquid into the mouth through the metallic tube 16, the sleeve being constructed 65 of suitable material to prevent injury to the mouth of the calf. The device is very simple in construction, and is detachably associated with the receptacle so that should the latter become injured beyond further use, 70 the device can be removed and associated with another receptacle.

While it is believed that from the foregoing description the nature and advantages of the invention will be readily apparent, we 75 desire to have it understood that we do not limit ourselves to what is herein shown and described, and that such changes may be resorted to when desired as fall within the scope of what is claimed.

80 What we claim is:

1. The combination with a receptacle, of a tubular member supported from the bottom centrally of the receptacle and disposed within the latter, a sleeve of relatively soft 85 material fitted on the tubular member and projecting above the latter and also above the receptacle, and a plurality of elements supporting said sleeve and terminally secured to the bottom of the receptacle at 90 spaced points about the tubular member.

2. The combination with a receptacle, of a tubular member arranged centrally within the receptacle and supported by the bottom thereof, a sleeve of relatively soft material 95 fitted on said tubular member and projecting above the latter and also above the receptacle and a plurality of elements terminally secured to the bottom of the receptacle about the tubular member, the upper 100 corresponding extremities of said elements being embedded in said sleeve for the purpose specified.

In testimony whereof we affix our signatures.

IKE BRATCHER.
OSCAR BURGHARDT.
